CONTAINER AND SEAL ASSEMBLY

**CROSS REFERENCE TO RELATED
APPLICATIONS**

This application is a continuation-in-part application of U.S. patent application Ser. No. 17/288,015, entitled “Container and Seal Assembly,” filed Apr. 23, 2021, which is a 371 National Stage Application of International Patent Application No. PCT/US20/19973, filed on Feb. 26, 2020, and entitled “Container and Seal Assembly,” which claims priority to, and the benefit under 35 U.S.C. § 119 of, U.S. Provisional Patent Application No. 62/810,709, filed Feb. 26, 2019, and entitled “TWO PIECE CONTAINER”;

U.S. patent application Ser. No. 17/288,017, entitled “Improved Three-Piece Container Assembly,” filed Apr. 23, 2021, which is a 371 National Stage Application of International Patent Application No. PCT/US20/19975, filed on Feb. 26, 2020, and entitled “Improved Three-Piece Container Assembly,” which claims priority to, and the benefit under 35 U.S.C. § 119 of, U.S. Provisional Patent Application No. 62/810,709, filed Feb. 26, 2019, and entitled “TWO PIECE CONTAINER”;

U.S. Design patent application No. 29/725,733, entitled “Container,” filed Feb. 26, 2020, now U.S. Pat. No. D.933, 324; and

U.S. Design patent application No. 29/725,734, entitled “Container Ring,” filed Feb. 26, 2020, now U.S. Pat. No. D.932,721, each of which are hereby incorporated by reference herein as if set forth in their entireties.

This application is also related to and hereby incorporates by reference the following U.S. patent applications:

U.S. Design patent application No. 29/725,732, entitled “CONTAINER,” filed on Feb. 26, 2020; and

U.S. Design patent application No. 29/725,731, entitled “CONTAINER LID,” filed on Feb. 26, 2020.

TECHNICAL FIELD

The present disclosure relates generally to containers and container lids.

BACKGROUND

Containers are a widely used component in a variety of industries. Wholesalers, merchants, and individuals use containers in a plethora of industries including, but not limited to: manufacturing, agriculture, beverage, entertainment, health care, food services, hospitality, fishing, retail, automotive, transportation, waste management, oil and gas, education, and construction. The paint industry in particular, as a liquid-based industry, heavily depends on containers for the majority of its packing, storing, and shipping requirements. As such, improvements to paint and other liquid-carrying containers may account for significant cost savings to a company’s bottom line.

As an initial matter, containers and lids can include inadequate sealing mechanisms that allow leakage and air intake. Further, in some applications, traditional containers tend to permit waste, as paint or other liquids often become trapped in various joints or seams of the container. Therefore, there is a long-felt but unresolved need for containers and lids, having a design that provides an improved sealing structure that provides a liquid-tight seal and limits the amount of product that may become trapped in various joints or seams of the container.

2

BRIEF SUMMARY OF DISCLOSURE

Briefly described and according to one embodiment, aspects of the present disclosure relate generally to containers and container lids, and more particularly to containers including a separate container ring and associated container lids. The present disclosure discusses a novel and unique container that provides several improvements over existing, traditional containers in the paint and other liquid-based industries. In various embodiments, the containers discussed herein increase product retention and are lower cost than traditional containers for storing similar goods. In at least one embodiment, the present container includes a separate container ring, which, in combination with the container design, may substantially eliminate one or more seams within the container (e.g., the combination of the container and ring). In this embodiment (and others), the present container may prevent product stored therein from being trapped in the one or more eliminated seams. Substantially eliminating one or more content-trapping seams may preserve original color content of tinted paint (e.g., by preventing tinted/coloring from being trapped in the seam) and enable a consumer to pour all paint/content out of the container such that no paint/content is left trapped within a joint or seam. As will be understood, a design that allows a consumer/user to pour out all paint/content may make such a container easier and/or less expensive to recycle.

Additionally, in particular embodiments, and as will be discussed herein, the present container is manufactured from plastic, as opposed to traditional containers manufactured from metal, such that production expenses may be decreased and container longevity may be increased.

According to a first aspect, the seal ring may include: A) an outer sidewall including: 1) an exterior outer sidewall surface including a substantially arcuate portion for interfacing with a corresponding semi-circular bead of a sidewall of a container in an attached configuration; 2) a top surface; 3) an upper portion outer surface substantially perpendicular to the top surface; and 4) a upper portion bottom surface substantially parallel to the top surface and perpendicular to the outer surface; B) a generally hook-shaped aperture including: 1) an aperture surface substantially parallel to the upper portion outer surface and intersecting with the upper portion bottom surface; and 2) an undercut surface substantially perpendicular to the aperture surface, wherein the undercut surface is configured to interface with a corresponding surface on the container in the attached configuration; C) an inner sidewall forming a seal structure for sealing an interior cavity of the container with a lid; and D) a floor connecting the inner sidewall and the outer sidewall.

According to a second aspect, the container may include the container of the first aspect or any other aspect, wherein the substantially arcuate portion of the exterior outer sidewall surface transitions to an exterior floor surface, the exterior floor surface substantially parallel to the upper portion outer surface.

According to a third aspect, the container may include the container of the second aspect or any other aspect, wherein the generally hook-shaped aperture and the substantially arcuate portion of the exterior outer sidewall surface seals the seal ring with the container in the attached configuration.

According to a fourth aspect, the container may include the container of the first aspect or any other aspect, wherein the floor slopes downwardly from the inner sidewall to the outer sidewall.

According to a fifth aspect, the container may include the container of the first aspect or any other aspect, wherein the

top surface transitions to an interior outer sidewall surface via a vertical wall substantially perpendicular to the top surface.

According to a sixth aspect, the container may include the container of the fifth aspect or any other aspect, wherein the outer sidewall and the inner sidewall form a generally u-shaped channel for receiving the lid for sealing the interior cavity of the container.

According to a seventh aspect, the container may include the container of the first aspect or any other aspect, wherein the inner sidewall includes: A) an inner seal surface; B) a substantially flat outer seal surface; and C) a ring bead integrally formed with the inner seal surface and extending from the inner seal surface toward an interior outer sidewall surface for engaging with a corresponding structure on the lid.

According to a eighth aspect, the container may include the container of the seventh aspect or any other aspect, wherein the ring bead includes an upper ring bead slope and a lower ring bead slope, the upper ring bead slope and lower ring bead slope culminating in a ring bead peak.

According to a ninth aspect, the container may include the container of the seventh aspect or any other aspect, wherein the inner seal surface and the substantially flat outer seal surface converge at a seal surface peak.

According to a tenth aspect, the container may include the container of the seventh aspect or any other aspect, wherein the substantially flat outer seal surface includes a seal ring notch for receiving a correspondingly shaped structure on a lid.

According to an eleventh aspect, the container may include the container of the tenth aspect or any other aspect, wherein the seal ring notch is positioned substantially opposite the ring bead.

According to a twelfth aspect, the container may include the container of the eleventh aspect or any other aspect, wherein the seal ring notch is substantially triangular, rectangular, or rounded.

According to a thirteenth aspect, the container may include the container of the first aspect or any other aspect, wherein the seal ring is plastic.

According to a fourteenth aspect, the container may include a container body including a bottom and an external wall extending from the bottom and defining an interior cavity, the external wall: A) including an exterior wall surface; B) terminating in a container rim area including: 1) a latch surface extending outwardly from the exterior wall surface; and 2) a semi-circular bead; and C) a seal ring attached to the container rim area and including: 1) an outer sidewall including: a) an exterior outer sidewall surface comprising a substantially arcuate portion interfacing with the semi-circular bead of the container rim area; b) a top surface; c) an upper portion outer surface substantially perpendicular to the top surface; d) a upper portion bottom surface substantially parallel to the top surface and perpendicular to the outer surface; e) a generally hook-shaped aperture including: i) an aperture surface substantially parallel to the upper portion outer surface and intersecting with the upper portion bottom surface; and ii) an undercut surface substantially perpendicular to the aperture surface, wherein the undercut surface interfaces with the latch surface of the container rim area; 2) an inner sidewall forming a seal structure for sealing the interior cavity of the container body with a lid; and 3) a floor connecting the inner sidewall and the outer sidewall.

According to a fifteenth aspect, the container may include the container of the fourteenth aspect or any other aspect,

wherein the substantially arcuate portion of the exterior outer sidewall surface transitions to an exterior floor surface, the exterior floor surface substantially parallel to the upper portion outer surface and to the exterior wall surface of the container body.

According to a sixteenth aspect, the container may include the container of the fifteenth aspect or any other aspect, wherein the generally hook-shaped aperture, the substantially arcuate portion of the exterior outer sidewall, and the exterior floor surface seals the seal ring with the container.

According to a seventeenth aspect, the container may include the container of the fourteenth aspect or any other aspect, wherein the floor slopes downwardly from the inner sidewall to the outer sidewall.

According to an eighteenth aspect, the container may include the container of the fourteenth aspect or any other aspect, wherein the top surface transitions to an interior outer sidewall surface via a vertical wall substantially perpendicular to the top surface.

According to a nineteenth aspect, the container may include the container of the fourteenth aspect or any other aspect, wherein the outer sidewall and the inner sidewall form a generally u-shaped channel for receiving the lid for sealing the interior cavity of the container body.

According to a twentieth aspect, the container may include the container of the fourteenth aspect or any other aspect, wherein the inner sidewall includes: A) an inner seal surface; B) a substantially flat outer seal surface; and C) a ring bead integrally formed with the inner seal surface and extending from the inner seal surface toward an interior outer sidewall surface for engaging with a corresponding structure on the lid.

According to a twenty-first aspect, the container may include the container of the twentieth aspect or any other aspect, wherein the ring bead includes an upper ring bead slope and a lower ring bead slope, the upper ring bead slope and lower ring bead slope culminating in a ring bead peak.

According to a twenty-second aspect, the container may include the container of the twenty-first aspect or any other aspect, wherein the inner seal surface and the substantially flat outer seal surface converge at a seal surface peak.

According to a twenty-third aspect, the container may include the container of the twenty-second aspect or any other aspect, wherein the substantially flat outer seal surface includes a seal ring notch for receiving a correspondingly shaped structure on the lid.

According to a twenty-fourth aspect, the container may include the container of the twenty-third aspect or any other aspect, wherein the seal ring notch is positioned substantially opposite the ring bead.

According to a twenty-fifth aspect, the container may include the container of the twenty-fourth aspect or any other aspect, wherein the seal ring notch is substantially triangular, rectangular, or rounded.

According to a twenty-sixth aspect, the container may include the container of the fourteenth aspect or any other aspect, wherein the container body and the seal ring are plastic.

According to a twenty-seventh aspect, the container may include the container of the fourteenth aspect or any other aspect, wherein the container includes the lid.

According to a twenty-eighth aspect, the seal ring may include: A) an outer sidewall including: 1) an arcuate portion for interfacing with a corresponding semi-circular bead of a sidewall of a container in an attached configuration including a first thickness; 2) a hook-shaped aperture; and 3) a seal

ring protrusion for engaging with the semi-circular bead in an attached configuration, the seal ring protrusion opposite an undercut surface of the hook-shaped aperture; B) a bottom surface sloping downwardly from an inner sidewall to the outer sidewall; C) a lower seal structure for engaging with a corresponding u-shaped crevice on a container and including: 1) a lower portion of the outer sidewall including a second thickness greater than the first thickness of the arcuate portion of the outer sidewall; 2) a cavity defined by the bottom structure and including: a) a first surface interfacing with a surface of the lower portion of the outer sidewall; b) a second surface forming a rounded transition to a bottom surface of the bottom structure; and c) an upper interior surface; and 3) a latch portion defined by the lower portion of the outer sidewall and the cavity.

According to a twenty-ninth aspect, the seal ring may include the seal ring of the twenty-eighth aspect or any other aspect, wherein a width of the cavity is between 0.75 cm and 1.5 cm.

According to a thirtieth aspect, the seal ring may include the seal ring of the twenty-ninth aspect or any other aspect, wherein the bottom surface slopes downwardly at an angle between 100 degrees and 130 degrees from the inner sidewall.

According to a thirty-first aspect, the seal ring may include the seal ring of the thirtieth aspect or any other aspect, wherein the inner sidewall includes a ring bead for engaging with a corresponding component on a container lid, wherein the ring bead includes a protrusion perpendicular to the inner sidewall.

According to a thirty-second aspect, the seal ring may include the seal ring of the thirty-first aspect or any other aspect, wherein the ring bead is trapezoidal in shape and further includes: A) a front surface, wherein the front surface is parallel to an interior surface of the inner sidewall; B) a top surface, wherein the top surface slopes downwardly from the interior surface of the inner sidewall to the front surface; and C) a bottom surface, wherein the bottom surface slopes downwardly from the front surface to the interior surface of the inner sidewall.

According to a thirty-third aspect, the seal ring may include the seal ring of the thirty-second aspect or any other aspect, wherein the distance between the seal ring protrusion and the undercut surface is between 0.25 cm and 1.5 cm.

According to a thirty-fourth aspect, the seal ring may include the seal ring of the thirty-third aspect or any other aspect, wherein the hook-shaped aperture, the seal ring protrusion, the arcuate portion, and the lower seal structure seal the ring with the container in an attached configuration.

According to a thirty-fifth aspect, the seal ring may include the seal ring of the thirty-fourth aspect or any other aspect, wherein the seal ring is plastic.

According to a thirty-sixth aspect, the seal ring may include: A) an outer sidewall including: 1) an arcuate portion for interfacing with a corresponding semi-circular bead of a sidewall of a container in an attached configuration including a first thickness; 2) a hook-shaped aperture; and 3) a seal ring protrusion for engaging with the semi-circular bead in an attached configuration, the seal ring protrusion opposite an undercut surface of the hook-shaped aperture; B) an inner sidewall including a ring bead for engaging with a corresponding component on a container lid; C) a bottom surface sloping downwardly from the inner sidewall to the outer sidewall; D) a lower seal structure for engaging with a corresponding u-shaped crevice on a container and including: 1) a lower portion of the outer sidewall including a second thickness greater than the first thickness of the

arcuate portion of the outer sidewall; 2) a cavity defined by the bottom structure and including: a) a first surface interfacing with a surface of the lower portion of the outer sidewall; b) a second surface forming a rounded transition to a bottom surface of the bottom structure; and c) an upper interior surface; and 3) a latch portion defined by the lower portion of the outer sidewall and the cavity.

According to a thirty-seventh aspect, the seal ring may include the seal ring of the thirty-sixth aspect or any other aspect, wherein a width of the cavity is between 0.75 cm and 1.5 cm.

According to a thirty-eighth aspect, the seal ring may include the seal ring of the thirty-seventh aspect or any other aspect, wherein the bottom surface slopes downwardly at an angle between 100 degrees and 130 degrees from the inner sidewall.

According to a thirty-ninth aspect, the seal ring may include the seal ring of the thirty-eighth aspect or any other aspect, wherein the ring bead includes a protrusion perpendicular to the inner sidewall.

According to a fortieth aspect, the seal ring may include the seal ring of the thirty-ninth aspect or any other aspect, wherein the ring bead is trapezoidal in shape and further includes: A) a front surface, wherein the front surface is parallel to an interior surface of the inner sidewall; B) a top surface, wherein the top surface slopes downwardly from the interior surface of the inner sidewall to the front surface; and C) a bottom surface, wherein the bottom surface slopes downwardly from the front surface to the interior surface of the inner sidewall.

According to a forty-first aspect, the seal ring may include the seal ring of the fortieth aspect or any other aspect, wherein the distance between the seal ring protrusion and the undercut surface is between 0.25 cm and 1.5 cm.

According to a forty-second aspect, the seal ring may include the seal ring of the forty-first aspect or any other aspect, wherein the hook-shaped aperture, the seal ring protrusion, the arcuate portion, and the lower seal structure seal the ring with the container in an attached configuration.

According to a forty-third aspect, the seal ring may include the seal ring of the forty-second aspect or any other aspect, wherein the seal ring is plastic.

According to a forty-fourth aspect, the container may include: a container body including a bottom and an external wall extending from the bottom to an upper end and defining an interior cavity, the external wall including: A) an exterior wall surface; B) a container rim area proximate the upper end and including: 1) a latch surface extending outwardly from the exterior wall surface; and 2) a semi-circular bead formed by an interior wall surface; and C) a ledge area below the container rim area, the ledge area integrally formed with the exterior wall and defining a u-shaped crevice for engaging with a corresponding lower seal structure of a seal ring; and the seal ring including: A) an outer sidewall including: 1) an arcuate portion for interfacing with the semi-circular bead of the interior wall surface of the container in an attached configuration; and 2) a seal ring protrusion for engaging with the semi-circular bead in the attached configuration; B) an inner sidewall forming a seal structure for sealing the interior cavity of the container with a lid; and C) a lower seal structure for engaging with the u-shaped crevice on the container and including: 1) a cavity; and 2) a latch portion defined by the outer sidewall and the cavity.

According to a forty-fifth aspect, the container may include the container of the forty-fourth aspect or any other aspect, wherein: A) the arcuate portion of the outer sidewall

includes a first thickness; and B) a lower portion of the outer sidewall includes a second thickness greater than the first thickness of the arcuate portion of the outer sidewall.

According to a forty-sixth aspect, the container may include the container of the forty-fifth aspect or any other aspect, wherein the seal ring includes: A) a hook-shaped aperture; and B) a seal ring protrusion for engaging with the semi-circular bead in an attached configuration, the seal ring protrusion opposite an undercut surface of the hook-shaped aperture.

According to a forty-seventh aspect, the container may include the container of the forty-sixth aspect or any other aspect, wherein the interior wall seal structure includes a ring bead for engaging with a corresponding component on the lid for sealing the interior cavity of the container.

These and other aspects, features, and benefits of the claimed embodiment(s) will become apparent from the following detailed written description of the embodiments and aspects taken in conjunction with the following drawings, although variations and modifications thereto may be effected without departing from the spirit and scope of the novel concepts of the disclosure.

BRIEF DESCRIPTION OF THE DRAWINGS

The accompanying drawings illustrate one or more embodiments and/or aspects of the disclosure and, together with the written description, serve to explain the principles of the disclosure. Wherever possible, the same reference numbers are used throughout the drawings to refer to the same or like elements of an embodiment, and wherein:

FIG. 1 is an exploded view of an exemplary container and container ring, according to one embodiment of the present disclosure;

FIG. 2 is a perspective view of an exemplary container, according to one embodiment of the present disclosure;

FIG. 3 is a perspective view of an exemplary container ring, according to one embodiment of the present disclosure;

FIG. 4 is a perspective view of an exemplary container ring and container in an attached configuration, according to one embodiment of the present disclosure;

FIG. 5 is a perspective view of an exemplary container ring, container and container lid in an attached configuration, according to one embodiment of the present disclosure;

FIG. 6 is a cross-sectional view of an exemplary container ring, container and container lid in an attached configuration, according to one embodiment of the present disclosure;

FIG. 7 is a cross sectional view of an exemplary container stacked on top of a container, container ring, and container lid in an attached configuration, according to one embodiment of the present disclosure;

FIG. 8 is an exploded view of an exemplary container and container ring, according to one embodiment of the present disclosure;

FIG. 9 is a top perspective view of an exemplary container, according to one embodiment of the present disclosure;

FIG. 10 is a bottom perspective view of an exemplary container, according to one embodiment of the present disclosure;

FIG. 11 is a top perspective view of an exemplary container ring, according to one embodiment of the present disclosure;

FIG. 12 is a bottom perspective view of an exemplary container ring, according to one embodiment of the present disclosure; and

FIG. 13 is a cross sectional view of an exemplary container and container ring in an attached configuration, according to one embodiment of the present disclosure.

DETAILED DESCRIPTION

For the purpose of promoting an understanding of the principles of the present disclosure, reference will now be made to the embodiments illustrated in the drawings and specific language will be used to describe the same. It will, nevertheless, be understood that no limitation of the scope of the disclosure is thereby intended; any alterations and further modifications of the described or illustrated embodiments, and any further applications of the principles of the disclosure as illustrated therein are contemplated as would normally occur to one skilled in the art to which the disclosure relates. All limitations of scope should be determined in accordance with, and as expressed in the claims.

Whether a term is capitalized is not considered definitive or limiting of the meaning of a term. As used in this document, a capitalized term shall have the same meaning as an uncapitalized term, unless the context of the usage specifically indicates that a more restrictive meaning for the capitalized term is intended. However, the capitalization or lack thereof within the remainder of this document is not intended to be necessarily limiting unless the context clearly indicates that such limitation is intended.

Overview

The above and further features of the disclosed exemplary container, container ring, and container lid will be recognized from the following detailed descriptions and drawings of particular embodiments. In various embodiments, a container with a rim is disclosed. In particular embodiments, the container includes a container body (e.g., external wall) that forms the outer casing of the container. In some embodiments, the container includes bail ear assemblies to provide a mechanism for attaching a handle to the container. According to at least one embodiment, the container includes a bottom panel to provide stability and support for the container as well as an encasing for material stored in the container. In particular embodiments, the container (e.g., the container rim) includes one or more seal surfaces to provide enhanced sealing properties when engaged with a container ring and sealed with a container lid.

In at least one embodiment, a container ring is disclosed for engaging with a container and container lid. In some embodiments, the container ring includes a u-shaped channel. In particular embodiments, the container ring includes one or more sidewalls including one or more seal surfaces for facilitating a liquid-tight seal when engaged with a container and/or container lid. In some embodiments, the container ring includes a ring bead for engaging with a corresponding structure on a container lid. In certain embodiments, the container ring includes an outer sidewall including a hook-shaped aperture for attaching to the container rim of a container. According to at least one embodiment, the container ring is circular in shape. In at least one embodiment, the container ring is square or rectangular in shape.

Furthermore, a container lid is disclosed for engaging with a container ring. In various embodiments, the container lid includes one or more seal surfaces to provide enhanced sealing properties when sealing a container (e.g., container ring). In particular embodiments, the container lid includes an undercut for engaging with a corresponding ring bead on

a container ring to facilitate a liquid-tight seal. In one or more embodiments, the container lid may be manufactured to fit any container shape (e.g., rectangular, ovoid, etc.). According to at least one embodiment, the container lid is circular in shape. In at least one embodiment, the container lid is square or rectangular in shape.

The container, container ring, and container lid discussed herein may be formed in any suitable way. In various embodiments, the container, container ring, and container lid are formed by injection molding. In particular embodiments, the container, container ring, and container lid are 3D printed or created via other additive manufacturing technique. In further embodiments, various components of the container, container ring, and container lid are formed or created separately, and the various components of the container, container ring, and container lid are joined or otherwise suitably connected to form the container, container ring, and container lid. In one embodiment, the container, container ring, and/or container lid may each be one piece and unitary.

The container, container ring, and container lid may be formed from any suitable material or materials for storing or transporting such materials. In various embodiments, the container, container ring, and container lid are manufactured from metal or composite material. In particular embodiments, the container, container ring, and container lid are manufactured from plastic (e.g., Polyethylene, High-Density Polyethylene, etc.).

As will be understood by one of ordinary skill in the art, the container, container ring, and container lid discussed herein may be used for storing and sealing any variety of materials, including, but not limited to: paints, oils, food, consumer goods, construction materials, inks, chemicals, lubricants, adhesives, coatings, roofing mastics, driveway sealers, flavorings, sanitation supplies, building products, ice melt compounds, powders, pet food, and other such materials.

Exemplary Embodiments

Turning now to FIG. 1, an exploded view of an exemplary container 1100 and container ring 1000 are shown, according to one embodiment of the present disclosure. In some embodiments, the container ring 1000 and the container 1100 are circular in shape and have a substantially similar radius. In various embodiments, the container ring 1000 and container 1100 may be rectangular or square in shape. In various embodiments, the container ring 1000 attaches to the container 1100 to facilitate a liquid-tight seal. In one or more embodiments, the container ring 1000 attaches to the container 1100 by placing the bottom 1008 of the container ring 1000 snugly around the rim 1104 of the container 1100 (as further discussed herein). In certain embodiments, the container ring 1000 and the container are manufactured out of plastic (e.g., Polyethylene, Polyethylene Terephthalate (PET), High-Density Polyethylene (HDPE), Polyvinyl Chloride (PVC), Low-Density Polyethylene (LDPE), Polypropylene (PP), Polystyrene (PP), etc.).

In particular embodiments, the container ring 1000 may include various components to facilitate a seal with the container 1100. In at least one embodiment, and as will be further discussed herein, the container ring includes an inner sidewall 1004 and an outer sidewall 1016 connected by a floor 1020. In one or more embodiments, and as shown in FIG. 1, the distance between the inner sidewall 1004 and the outer sidewall 1016 may be any suitable distance (e.g., 0.8-1.2 cm, 4.8-5.2 cm, 9.8-10.2 cm, etc.). In some embodi-

ments, and as will be further described herein, a container lid (e.g., a plug) includes corresponding sealing components, that may align and engage with the inner sidewall 1004 of the container ring 1000 to provide a liquid-tight seal when pressed together.

In one embodiment, and as shown in FIG. 1, the container 1100 includes a container body 1102. In particular embodiments, the container body 1102 includes an external wall 1110 to enclose the container 1100 and provide a solid base for stability. In some embodiments, the external wall 1110 may include graphical information (e.g., signage). In various embodiments, the container body 1102 terminates at an open end, whereby the open end includes a container rim 1104 around its circumference. In certain embodiments, and as will be further discussed herein, the container rim 1104 includes design features to facilitate a liquid-tight seal when engaged with a container ring 1000. Further, in various embodiments, the container 1100 includes a container bottom 1108 to provide stability and support for the container 1000 when resting on a surface.

FIG. 2 shows an exemplary container 1100, according to one embodiment of the present disclosure. In the embodiment shown in FIG. 2, plastic bail ears 1106 are included on the external wall 1110 of the container body 1102, such that a handle may be attached to the container 1100 to facilitate carrying or lifting of the container. In various embodiments, the bail ears 1106 may be circular, pentagonal, rectangular, or any suitable shape. In particular embodiments, the bail ears 1106 may be affixed to the external wall 1110 of the container body 1102, or, in one or more embodiments, the bail ears 1106 may be an integral component of external wall 1110 of the container body 1102.

FIG. 3 shows an exemplary container ring 1000, according to one embodiment of the present disclosure. In particular embodiments, and as shown in FIG. 3, a top surface 1026 of the outer sidewall 1016 is at a higher elevation than a top surface 1010 of the inner sidewall 1004 relative to the container ring floor 1020. In certain embodiments, the thickness of the inner sidewall 1004 is less than the thickness of the outer sidewall 1016. As will be further discussed herein, in some embodiments, the outer sidewall 1016 includes an aperture 1012 beneath the top surface 1026 to facilitate attachment of the container ring 1000 to the rim of a container. In at least one embodiment, the outer sidewall 1016 extends upward at an angle greater than ninety degrees from the container ring floor 1020. In one or more embodiments, the inner sidewall 1004 has a smaller radius than the outer sidewall 1016, whereby the difference in radii is substantially equivalent to the width of the container ring floor 1020. In some embodiments, the width of container floor 1020 and the angle of the outer sidewall 1026 generally prevent liquid from getting trapped in the container ring 1000. In at least one embodiment, the floor 1020 of the container ring 1000 includes a generally smooth surface.

Turning now to FIG. 4, a perspective view of an exemplary container ring 1000 attached to an exemplary container 1100 is shown, according to one embodiment of the present disclosure. In various embodiments, and as shown in FIG. 4, when the container ring 1000 is attached to the container 1100, the container rim 1104 of the container 1100 is substantially enveloped by the container ring 1000, such that an outer surface 1024 of the outer sidewall 1016 extends over the edge of the container rim 1104.

FIG. 5 shows an exemplary container ring 1000, container 1100, and container lid 500 in an attached configuration, according to one embodiment of the present disclosure. In particular embodiments, and as will be discussed herein,

11

various sealing components of the container lid 500 engage with the inner sidewall (not shown) of the container ring 1000 to facilitate a liquid-tight seal of the container 1100.

Now referring to FIG. 6, a cross-sectional view of an exemplary container ring, container 1101, and container lid 501 in an attached configuration is shown, according to one embodiment of the present disclosure. In various embodiments, the container 1101 includes an external wall 1110 with an outer surface 1122 and an inner surface 1112. In certain embodiments, the external wall 1110 of the container 1101 extends upward from the container bottom and transitions into a container rim 1104 at the upper end of the container 1101. In at least one embodiment, the container rim 1104 extends outward from the outer surface 1122 of the external wall 1110 to form a latch surface 1032 for engaging with the container ring 1001, as will be further discussed herein. In certain embodiments, and as shown in FIG. 6, the upper portion 1116 of the inner surface 1112 of the external wall 1110 protrudes outwardly from the external wall 1110 and establishes a generally semi-circular bead 1118. In one or more embodiments, the bead 1118 may have a radius less than 1 cm. In particular embodiments, the generally semi-circular bead 1118 transitions downward to an exterior floor surface 1034. In one or more embodiments, the exterior floor surface 1034 may be substantially parallel to the external wall 1110 of the container 1101.

In particular embodiments, the container ring 1001 includes a generally u-shaped channel 1052. In the embodiment shown in FIG. 6, the u-shaped channel 1052 (from a cross-sectional perspective) includes two sidewalls 1004, 1016 connected by a floor 1020 that generally slopes from the inner sidewall 1004 downwardly to the outer sidewall 1016, whereby the outer sidewall 1016 and the floor 1020 form a substantially rounded connection 1018. In certain embodiments, the floor 1020 may slope at an angle between forty-five and ninety degrees, preferably at an angle between forty-five and fifty degrees, relative to the outer sidewall 1016. In one or more embodiments, and as shown in FIG. 6, the distance between the inner sidewall 1004 and the outer sidewall 1016 may be any suitable distance (e.g., 0.8-1.2 cm, 4.8-5.2 cm, 9.8-10.2 cm, etc.).

As will be further discussed below, the inner sidewall 1004 includes seal surfaces 1002, 1008, and integrally formed protrusions (e.g., ring bead 1014) of the container ring 1000. In particular embodiments, the seal surfaces 1002, 1008 of the inner sidewall 1004 converge at an upper portion of the container ring 1001 into a substantially trapezoidal peak (e.g., top surface 1010), which fits into a corresponding trapezoidal cavity 622 on the container lid 501. In certain embodiments, top surface 1010 (and the corresponding cavity on the container lid) may be substantially rectangular. In particular embodiments, top surface 1010 (and the corresponding cavity on the container lid) may be substantially rounded. In some embodiments, the inner sidewall 1004 may include a notch (not shown) on the seal surface 1008 for engaging with a corresponding notch on a container lid. In one embodiment, the seal surfaces 1002, 1008 may be composed of an elastomer. In another embodiment, the seal surfaces 1002, 1008 are composed of plastic. In various embodiments, and as shown in FIG. 6, the seal surfaces 1002, 1008 of the container ring 1001 are substantially flush against the seal surfaces 654, 656 of the container lid 501 (including the trapezoidal cavity 622), such that a liquid-tight seal is facilitated.

Continuing with the embodiment shown in FIG. 6, the inner sidewall 1004 includes a ring bead 1014 (or other suitable protrusion) that protrudes into the u-shaped channel

12

1052 of the container ring 1001. In various embodiments, the ring bead 1014 may be substantially trapezoidal or substantially rounded in shape. In one or more embodiments, the ring bead 1014 (e.g., protrusion) engages with a corresponding seal structure on the container lid 501, such that a liquid-tight seal between the container ring 1001 and the container lid 501 may be formed. For example, in particular embodiments, the ring bead 1014 engages with a corresponding undercut 518 on the container lid, and, in combination with the seal surfaces 1002, 1008, facilitates a liquid-tight seal between the container ring 1000 and the lid 501. As will be understood from discussions herein, the inner sidewall 1004 is received within a generally u-shaped channel of a container lid 501, and the seal surfaces 1002, 1008 and ring bead 1014 help create a seal between the inner sidewall 1004 and the container lid 501, thereby sealing an interior/storage area of the container.

Further continuing with the embodiment shown in FIG. 6, the outer sidewall 1016 includes various features for engaging with, and sealing a container 1101. In certain embodiments, the outer sidewall 1016 may be substantially concave. In particular embodiments, the outer sidewall 1016 includes an upper portion 1028 that includes an aperture 1012, such that the upper portion 1028 of the outer sidewall 1016 is substantially hook-shaped. In at least one embodiment, and as shown in FIG. 6, the aperture 1012 engages with the container rim 1104, whereby the bead 1118 on the upper portion 1116 of the inner surface 1112 of the external wall 1110 is flush against the outer sidewall 1016 of the container ring 1001, such that a liquid-tight seal is formed. In particular embodiments, the apex 1120 of the bead 1118 on the upper portion 1116 of the inner surface 1112 of the external wall 1110 makes contact with the outer sidewall 1016 of the container ring 1001. In these embodiments (and others), the exterior floor surface 1034 is flush against the inner surface 1112 or the external wall 1110 such that a liquid-tight seal is formed. In one or more embodiments, pressure exerted on the container lid 501 is transferred to the interface between the bead 1118 on the container 1101 and the hook and latch structure of the seal container ring 1001 and container 1101, such that sealing properties are increased.

In one or more embodiments, the upper portion 1028 of the outer sidewall 1016 includes a top surface 1026. In particular embodiments, the top surface 1026 is substantially flat and substantially parallel to the container bottom. In certain embodiments, the top surface 1026 transitions down to a secondary surface 1030 of the outer sidewall 1016 via a vertical wall 1022. In one or more embodiments, the top surface 1026 of the upper portion 1028 is at a higher elevation from the bottom of the container than the secondary surface 1030 of the outer sidewall 1016. In at least one embodiment, the secondary surface 1030 is substantially flat and substantially parallel to the container bottom.

In particular embodiments, the upper portion 1028 of the outer sidewall 1016 of the container ring 1001 includes a bottom surface 1027 that is substantially parallel to the top surface 1026. In some embodiments, the top surface 1026 and the bottom surface 1027 of the upper portion 1028 of the outer sidewall 1016 are integrally connected by an outer surface 1024 of the outer sidewall 1016. In some embodiments, the distance between the top surface 1026 of the upper portion 1028 and the bottom surface 1027 of the upper portion 1028 may be less than 30 mm.

In at least one embodiment, the top surface 1026 of the upper portion 1028 of the outer sidewall 1016 is at a first distance from the bottom surface of the container ring 1001,

and the top surface **1010** of the inner sidewall **1004** (e.g., the trapezoidal peak) is at a second distance from the bottom surface of the container ring **1001**, where the first distance is greater than the second distance. In particular embodiments, the “tiered elevation” of the top surface **1026** of the outer sidewall **1016** and the top surface **1010** of the inner sidewall **1004** (e.g., the trapezoidal peak) may help increase stability and load distribution when two (or more) containers **1101** and container rings **1001** are stacked together (e.g., for shipping, without lids), as portions of the container bottom may match the tiered elevation of the sidewalls **1004**, **1016** of the container ring **1001**.

Turning now to FIG. 7, a cross sectional view of an exemplary container **1103** stacked on top of a container **1101**, container ring **1001**, and container lid **501** in an attached configuration is shown, according to one embodiment of the present disclosure. As shown in the present embodiment, a container bottom **301** sits on top of a container lid **501** engaged in a seal with a container ring **1001** attached to a container **1101**. In various embodiments, the container bottom **301** includes legs **302**, **304** to provide stability for the container **1103**. In various embodiments, the upper leg **302** includes a base **324** and the lower leg **304** includes a base **322**. In particular embodiments, the bases **322**, **324** are substantially parallel to the container bottom and provide support when the container **1103** is rested on a surface.

In various embodiments, and as shown in FIG. 7, the substantially flat shape of the top surface **1026** of the outer sidewall **1016** provides a level surface for the base **324** of the upper leg **302** to rest upon. In these embodiments (and others), the lower leg **304** and the upper leg **302** may straddle the secondary surface **1030** of the outer sidewall **1016**.

As discussed above, and shown in FIG. 7, the tiered elevation of the sidewalls **1004**, **1016** of the container ring **1001** in combination with the vertical height of the lid **501**, provides stability and load distribution when two (or more) containers **1101**, **1103** with container rings **1001** attached are stacked together.

Now referring to FIG. 8, an exploded view of an exemplary container **8100** and container ring **8000** is shown, according to one embodiment of the present disclosure. In some embodiments, the container ring **8000** and the container **8100** are circular in shape and have a substantially similar diameter. In various embodiments, the container ring **8000** and container **8100** may be rectangular or square in shape.

In some embodiments, the container ring **8000** attaches to the container **8100** to facilitate a liquid-tight seal. In one or more embodiments, the container ring **8000** attaches to the container **8100** by securing an aperture of the container ring **8000** over the rim of the container **8100**, in combination with the engagement of the container’s u-shaped crevice and the container ring’s lower seal structure (as further discussed herein).

The container ring **8000** and the container **8100** may be constructed of any suitable material or materials. In many embodiments, the container ring **8000** and the container **8100** are constructed of the same material. In some embodiments, the container ring **8000** and the container **8100** are constructed of different materials. In certain embodiments, the container ring **8000** and the container **8100** are manufactured out of plastic (e.g., Polyethylene, Polyethylene Terephthalate (PET), High-Density Polyethylene (HDPE), Polyvinyl Chloride (PVC), Low-Density Polyethylene (LDPE), Polypropylene (PP), Polystyrene (PP), etc.).

In particular embodiments, the container ring **8000** may include various components to facilitate a seal with the container **8100**. In at least one embodiment, and as will be further discussed herein, the container ring includes a u-shaped channel **8052** formed by an inner sidewall **8004** and an outer sidewall **8016** connected by a floor **8020**. As will be understood from discussions herein, in some embodiments, the u-shaped channel **8052** receives a portion of a lid (e.g., container lid **500** discussed herein). As also will be understood from discussions herein, a container lid may include corresponding sealing components that may align and engage with the inner sidewall **8004** of the container ring **8000** to cover the container **8100** and provide a liquid-tight seal when pressed together.

In one embodiment, and as shown in FIG. 8, the container **8100** includes a container body **8102**. In particular embodiments, the container body **8102** includes an external wall **8110** extending from a circular bottom **8108**. In at least one embodiment, the external wall encloses and/or forms an internal cavity (e.g., storage area) of the container **8100**. In various embodiments, the container body **8102** terminates at a container rim **8104** formed around the container body **8102** circumference. In certain embodiments, and as will be further discussed herein, the external wall **8110** forms features to facilitate a liquid-tight seal when engaged with a container ring **8000**.

FIGS. 9 and 10 show a top perspective view and a bottom perspective view of exemplary container **8100**, according to one embodiment of the present disclosure. In some embodiments, the external wall **8110** may include graphical information (e.g., signage). As shown in the embodiments of FIGS. 9 and 10, the container **8100** may include one or more bail ears **8106** attached to the external wall **8110** of the container body **8102**, such that a handle may be attached to the container **8100** to facilitate carrying or lifting of the container. In various embodiments, the bail ears **8106** may be circular, pentagonal, rectangular, or any suitable shape. In particular embodiments, the bail ears **8106** may be affixed to the external wall **8110** of the container body **8102**, or, in one or more embodiments, the bail ears **8106** may be an integral component of external wall **8110** of the container body **8102**. In certain embodiments, the container **8100** may include a container bottom **8108** for providing support for the container **8100**. In various embodiments, the container bottom **8108** and external wall **8110** combine to form a cavity for storing things within the container **8100**.

Turning now to FIG. 11, this figure shows a top perspective view of an exemplary container ring **8000**, according to one embodiment of the present disclosure. In particular embodiments, and as shown in FIG. 11, a top surface **8026** of the outer sidewall **8016** is at a higher elevation than a top surface **8010** of the inner sidewall **8004** relative to the container ring floor **8020**.

As will be further discussed herein, in some embodiments, the outer sidewall **8016** forms an aperture **8012** beneath the top surface **8026** to facilitate attachment of the container ring **8000** to the rim of a container. In one or more embodiments, the inner sidewall **8004** has a smaller diameter than the outer sidewall **8016**, whereby the difference in diameter is substantially equivalent to the width of the container ring floor **8020**. In some embodiments, the width of container floor **8020** and the angle of the outer sidewall **8026** generally prevent liquid from getting trapped in the container ring **8000**. In at least one embodiment, the floor **8020** of the container ring **8000** includes a generally smooth surface.

FIG. 12 shows a bottom perspective view of an exemplary container ring **8000**, according to one embodiment of the present disclosure. The embodiment shown in FIG. 12 includes an aperture **8012** beneath the top surface **8026** of the container ring **8000**. In particular embodiments, the aperture **8012** facilitates attachment to a container by providing a snug, liquid-tight connection to the rim of a container. In various embodiments, and as will be further described herein, the container ring **8000** includes various seal features (e.g., hooks, notches, protrusions, etc.) that engage with corresponding features on the container to provide a liquid-tight seal and prevent undesired exposure and/or degradation of a product being sealed.

Turning now to FIG. 13, a cross-sectional view of an exemplary container **8100** and container ring **8000** in an attached configuration is shown, according to one embodiment of the present disclosure. In particular embodiments, the exemplary container **8100** and container ring **8000** include various seal features to facilitate formation of a liquid-tight seal when in an attached configuration. According to particular embodiments, the exemplary container **8100** and container/seal ring **8000** include: i) a u-shaped crevice (container **8100**) for engaging with a lower seal structure (seal ring **8000**); ii) a container rim area **8104** with latch-like features for engaging with hook-like features on a seal ring **8000**; and iii) an inner sidewall **8004** (seal ring **8000**) with various seal features (e.g., ring bead **8014**) for engaging with corresponding seal features on a container lid (not shown).

In various embodiments, the container **8100** includes an external wall **8110** with an outer surface **8122** and an inner surface **8112**. In at least one embodiment, the distance (e.g., thickness) between the inner surface **8112** and the outer surface **8122** gradually increases from the bottom portion **8212** of the ledge area **8210** to the top of the ledge area (which forms the u-shaped crevice **8204**). In particular embodiments, the bottom portion **8212** of the ledge area **8210** may be between about 7 and 30 cm from the container bottom (e.g., 7 cm, 10 cm, 15 cm, 25 cm, etc.). In certain embodiments, and as shown in FIG. 13, the distance (e.g., thickness) between the inner surface **8112** and the outer surface **8122** abruptly decreases at the top of the ledge area **8210** and remains relatively consistent from the top ledge area to the bottom of the semi-circular bead **8118** (as will be further discussed herein).

In certain embodiments, the external wall **8110** of the container **8100** extends upward from the container bottom and transitions into a container rim **8104** at the upper end of the container **8100** (e.g., above the semi-circular bead **8118**). In at least one embodiment, the container rim **8104** extends outward from the outer surface **8122** of the external wall **8110** to form a latch surface **8032** for engaging with the container ring **8000**, as will be further discussed herein.

In certain embodiments, and as shown in FIG. 13, the upper portion **8116** of the inner surface **8112** of the external wall **8110** protrudes outwardly from the external wall **8110** and forms a generally semi-circular bead **8118**. In one or more embodiments, the semi-circular bead **8118** may have a radius less than 1 cm. In particular embodiments, the semi-circular bead **8118** transitions downward to the top portion of the ledge area **8210**.

In particular embodiments, the container ring **8000** includes a generally u-shaped channel **8052**. In the embodiment shown in FIG. 13, the u-shaped channel **8052** (from a cross-sectional perspective) includes two sidewalls **8004**, **8016** connected by a floor **8020** that generally slopes from the inner sidewall **8004** downwardly to the outer sidewall

8016, whereby the outer sidewall **8016** and the floor **8020** form a substantially rounded connection **8018**. In certain embodiments, the floor **8020** (e.g., bottom surface) may slope at an angle between forty-five and ninety degrees. In some embodiments, the floor **8020** slopes at an angle between forty-five and fifty degrees, relative to the outer sidewall **8016**. In particular embodiments, the floor **8020** (e.g., bottom surface) may slope at an angle between 95 and 150 degrees relative to the inner sidewall **8004**. In one or more embodiments, and as shown in FIG. 13, the distance between the inner sidewall **8004** and the outer sidewall **8016** may be any suitable distance (e.g., 0.8-1.2 cm, 4.8-5.2 cm, 9.8-10.2 cm, etc.). In at least one embodiment, the floor **8020** of the container ring **8000** includes a generally smooth surface.

In particular embodiments, the outer sidewall **8016** is substantially arcuate (e.g., concave) in shape. In certain embodiments, the outer sidewall **8016** is substantially arcuate such that it forms a flush connection with the semi-circular bead **8118** of a container **8100** when in an attached configuration. In at least one embodiment, the bottom portion of the outer sidewall **8016** is a greater thickness than the top portion of the outer sidewall **8016** (as shown in the cross-sectional view of FIG. 13). In various embodiments, a bottom portion of the outer sidewall **8016** transitions into a lower seal structure **8202** for engaging with a corresponding ledge area **8210** of a container **8100**.

As will be further discussed below, the inner sidewall **30** **8004** includes seal surfaces **8002**, **8008**, and integrally formed protrusions (e.g., ring bead **8014**) of the container ring **8000**. In particular embodiments, the seal surfaces **8002**, **8008** of the inner sidewall **8004** converge at an upper portion of the container ring **8000** into a substantially trapezoidal peak (e.g., top surface **8010**), which fits into a corresponding trapezoidal cavity on a container lid (not shown). In certain embodiments, top surface **8010** may be substantially rectangular. In particular embodiments, top surface **8010** may be substantially rounded. In one embodiment, the seal surfaces **8002**, **8008** may be composed of an elastomer. In another embodiment, the seal surfaces **8002**, **8008** are composed of plastic. In various embodiments, the seal surfaces **8002**, **8008** of the container ring **8000** are substantially flush against the seal surfaces of a container lid (including a trapezoidal cavity), such that a liquid-tight seal is facilitated.

Continuing with the embodiment shown in FIG. 13, the inner sidewall **8004** includes a ring bead **8014** (or other suitable protrusion) that protrudes into the u-shaped channel **8052** of the container ring **8000**. In various embodiments, the ring bead **8014** may be substantially trapezoidal or substantially rounded in shape. In certain embodiments, the ring bead **8014** may include a front surface substantially parallel to the inner sidewall **8004**. In certain embodiments, the ring bead **8014** may include a top surface that slopes downwardly from the inner sidewall **8004** to the front surface of the ring bead **8014**. In these embodiments (and others), the ring bead **8014** may include a substantially concave bottom surface that slopes downwardly from the front surface of the ring bead **8014** to the inner sidewall **8004**. In one or more embodiments, the ring bead **8014** (e.g., protrusion) engages with a corresponding seal structure on a container lid (not shown), such that a liquid-tight seal between the container ring **8000** and the container lid may be formed. For example, in particular embodiments, the ring bead **8014** engages with a corresponding undercut on the container lid, and, in combination with the seal surfaces **8002**, **8008**, facilitates a liquid-tight seal between the con-

tainer ring **8000** and the lid. As will be understood from discussions herein, the inner sidewall **8004** is received within a generally u-shaped channel of a container lid, and the seal surfaces **8002**, **8008** and ring bead **8014** help create a seal between the inner sidewall **8004** and the container lid, thereby sealing an interior/storage area of the container.

Further continuing with the embodiment shown in FIG. 13, the outer sidewall **8016** includes various features for engaging with, and sealing a container **8100**. In certain embodiments, the outer sidewall **8016** may be substantially concave. In particular embodiments, the outer sidewall **8016** includes an upper portion **8028** that includes an aperture **8012**, such that the upper portion **8028** of the outer sidewall **8016** is substantially hook-shaped.

In particular embodiments, the outer surface of the outer sidewall **8016** includes a seal ring protrusion **8200** that engages with the semi-circular bead **8118** on the container **8100**. In one or more embodiments, the seal ring protrusion **8200** is substantially triangular. In some embodiments, the semi-circular bead **8118** may include a corresponding notch (not shown) to facilitate engagement with the seal ring **8200**. In the embodiment shown in FIG. 13, the bead **8118** does not include a corresponding notch, such that when the container and container ring are engaged, the seal ring protrusion **8200** establishes a tighter connection with the semi-circular bead **8118**, which further improves the sealing functionality of a connected container **8100** and container ring **8000**. In particular embodiments, the seal ring protrusion **8200** is substantially opposite the latch surface **8032** (e.g., undercut surface) of the container rim **8104**. In some embodiments, the distance between the seal ring protrusion **8200** and the latch surface **8032** is between 0.1 cm and 2.0 cm (e.g., 0.5 cm, 1.0 cm, etc.).

In certain embodiments, the lower portion of the outer sidewall **8016** includes a lower seal structure **8202** to facilitate engagement with the u-shaped crevice **8204** on the container. In some embodiments, the lower seal structure **8202** includes a cavity **8214** between 0.3 cm and 2.0 cm in width (e.g., 0.5 cm, 1.0 cm, etc.). In at least one embodiment, the lower seal structure **8202** also includes an outer leg **8208**, whereby the outer leg **8208** is an extension of the exterior sidewall **8110**. In at least one embodiment, and as shown in FIG. 13, the lower seal structure **8202** engages with the ledge area **8210** and u-shaped crevice **8204**. In these embodiments (and others), an outer leg **8208** (e.g., latch portion) of the container ring **8000** engages with the u-shaped crevice **8204**, and the inner crevice arm **8206** of the external wall **8110** of the container **8100** engages with the cavity **8214**.

In at least one embodiment, and as shown in FIG. 13, the aperture **8012** engages with the container rim **8104**. In various embodiments, the engagement of the aperture **8012** with the container rim **8104** and the lower seal structure **8202** with the u-shaped crevice **8204**, and the engagement of the bead **8118** on the upper portion **8116** of the inner surface **8112** of the external wall **8110** with the outer sidewall **8016** of the container ring **8000** (including with the seal ring **8200**), forms a liquid-tight seal. In particular embodiments, the apex **8120** of the bead **8118** on the upper portion **8116** of the inner surface **8112** of the external wall **8110** makes contact with the outer sidewall **8016** of the container ring **8000**. In one or more embodiments, pressure exerted on the container lid is transferred to the interface between the bead **8118** on the container **8100** and the hook and latch structure of the seal container ring **8000** and container **8100**, such that sealing properties are increased.

In one or more embodiments, the upper portion **8028** of the outer sidewall **8016** includes a top surface **8026**. In particular embodiments, the top surface **8026** is substantially flat and substantially parallel to the container bottom. In certain embodiments, the top surface **8026** transitions down to a secondary surface **8030** of the outer sidewall **8016** via a vertical wall **8022**. In one or more embodiments, the top surface **8026** of the upper portion **8028** is at a higher elevation from the bottom of the container than the secondary surface **8030** of the outer sidewall **8016**. In at least one embodiment, the secondary surface **8030** is substantially flat and substantially parallel to the container bottom.

In particular embodiments, the upper portion **8028** of the outer sidewall **8016** of the container ring **8001** includes a bottom surface **8027** that angles upward to form a substantially triangular shape. In these embodiments (and others), the triangular shape of the bottom surface **8027** facilitates secure attachment between the container **8100** and container rim **8000** by forming a ledge-like structure for the container rim to latch onto. In some embodiments, the top surface **8026** and the bottom surface **8027** of the upper portion **8028** of the outer sidewall **8016** are integrally connected by an outer surface **8024** of the outer sidewall **8016**. In some embodiments, the distance between the top surface **8026** of the upper portion **8028** and the bottom surface **8027** of the upper portion **8028** may be less than 30 mm.

In at least one embodiment, the top surface **8026** of the upper portion **8028** of the outer sidewall **8016** is at a first distance from the bottom surface of the container ring **8000**, and the top surface **8010** of the inner sidewall **8004** (e.g., the trapezoidal peak) is at a second distance from the bottom surface of the container ring **8000**, where the first distance is greater than the second distance. In particular embodiments, the “tiered elevation” of the top surface **8026** of the outer sidewall **8016** and the top surface **8010** of the inner sidewall **8004** (e.g., the trapezoidal peak) may help increase stability and load distribution when two (or more) containers **8100** and container rings **8000** are stacked together (e.g., for shipping, without lids), as portions of the container bottom may match the tiered elevation of the sidewalls **8004**, **8016** of the container ring **8000**.

CONCLUSION

Accordingly, it will be readily understood by those persons skilled in the art that, in view of the above detailed description of the various embodiments and articles of the present disclosure, the present disclosure is susceptible of broad utility and application. Many methods, embodiments, and adaptations of the present disclosure other than those herein described, as well as many variations, modifications, and equivalent arrangements will be apparent from or reasonably suggested by the present disclosure and the above detailed description thereof, without departing from the substance or scope of the present disclosure. Accordingly, while the present disclosure is described herein in detail in relation to various embodiments, it is to be understood that this detailed description is only illustrative and exemplary of the present disclosure and is made for purposes of providing a full and enabling disclosure of the present disclosure. The detailed description set forth herein is not intended nor is to be construed to limit the present disclosure or otherwise to exclude any such other embodiments, adaptations, variations, modifications, and equivalent arrangements of the present disclosure. The scope of the present disclosure is defined solely by the claims appended hereto and the equivalents thereof.

What is claimed is:

1. A container assembly comprising:
a container and a seal ring, wherein:

a central vertical axis intersects a center point of a bottom of the container and a center point of a top of the container and a radial axis intersects the central vertical axis and is perpendicular to the central vertical axis;

the container comprises a container sidewall comprising a ledge configured to engage at least a portion of the seal ring when the seal ring is in an attached configuration with respect to the container, the ledge comprising a u-shaped crevice that is (i) internally located within the container and (ii) configured to engage with at least a portion of a lower seal structure of the seal ring, wherein:

the u-shaped crevice comprises a first crevice sidewall, a second crevice sidewall radially outward from the first crevice sidewall, and a crevice floor extending between the first crevice sidewall and the second crevice sidewall, and

the first crevice sidewall and a portion of an interior surface of the container sidewall at least partially define a crevice arm projecting from the container sidewall; and

the seal ring comprises:

an outer sidewall comprising:

an arcuate portion for interfacing with a corresponding semi-circular bead of a sidewall of a container in the attached configuration;

an outer lip defining an annular channel having an upper closed end and a lower open end, the upper closed end being closer to the top of the container than the lower open end when the seal ring is in the attached configuration; and

a seal ring protrusion for engaging with the semi-circular bead in the attached configuration, the seal ring protrusion opposite an undercut surface of the annular channel;

a bottom surface extending from an inner sidewall toward the outer sidewall;

the lower seal structure, wherein the lower seal structure is configured to engage with the u-shaped crevice of the container and comprises: a lower portion of the outer sidewall;

a cavity defined by a bottom structure of the lower portion of the outer sidewall, wherein the cavity comprises:

a first surface interfacing with a surface of the lower portion of the outer sidewall, the first surface extending at least partially in a vertical direction parallel to the central vertical axis; a second surface forming a rounded transition to the bottom surface, the second surface extending at least partially in the vertical direction, wherein at least a portion of the second surface faces at least a portion of the first surface; and an upper interior surface extending at least partially in a radial direction, the upper interior surface having a radially outermost edge intersecting the first surface and a radially innermost edge intersecting the second surface,

when the seal ring is in the attached configuration with respect to the container, the radial axis simultaneously intersects (i) the first crevice sidewall of the container, (ii) the second crevice sidewall of the container, (iii) the portion of the interior surface

of the container sidewall, (iv) the crevice arm of the container, (v) a portion of an exterior surface of the container sidewall, (vi) the at least a portion of the first surface of the seal ring, (vii) the at least a portion of the second surface of the seal ring, and (viii) the bottom surface of the seal ring; and a latch portion defined by the lower portion of the outer sidewall and the cavity, the latch portion projecting outwardly from the seal ring.

2. The container assembly of claim 1, wherein the bottom surface slopes radially outwardly and downwardly toward the bottom of the container when the seal ring is in the attached configuration, at an angle between 100 degrees and 130 degrees from the inner sidewall.

3. The container assembly of claim 2, wherein the inner sidewall comprises a ring bead for engaging with a corresponding component on a container lid, wherein the ring bead protrudes substantially perpendicularly to the inner sidewall.

4. The container assembly of claim 3, wherein the ring bead is trapezoidal in shape and further comprises:

a front surface, wherein the front surface is parallel to an interior surface of the inner sidewall;

a top surface, wherein the top surface slopes downwardly toward the bottom of the container when the seal ring is in the attached configuration, from the interior surface of the inner sidewall to the front surface; and

a bottom surface, wherein the bottom surface slopes downwardly toward the bottom of the container when the seal ring is in the attached configuration, from the front surface to the interior surface of the inner sidewall.

5. The container assembly of claim 4, wherein a distance between the seal ring protrusion and the undercut surface is between 0.25 cm and 1.5 cm.

6. The container assembly of claim 5, wherein the annular channel, the seal ring protrusion, the arcuate portion, and the lower seal structure seal the seal ring with the container in the attached configuration.

7. The container assembly of claim 1, wherein: the u-shaped crevice is upwardly open toward the top of the container,

the container comprises a container sidewall having a lower portion and an upper portion,

at least some of the upper portion is configured to engage with at least some of the outer sidewall of the seal ring when the seal ring is in the attached configuration with respect to the container,

the ledge is disposed between the lower portion and the upper portion,

the container sidewall has a first thickness at a location within the lower portion and a second thickness at a location of the ledge, the second thickness being greater than the first thickness, and

the container sidewall gradually increases in thickness from the first thickness to the second thickness.

8. The container assembly of claim 1, wherein when the seal ring is in the attached configuration with respect to the container, the cavity of the seal ring at least partially receives the crevice arm of the container and the u-shaped crevice of the container at least partially receives the latch portion of the seal ring to thereby form an interlocking seal between the seal ring and the container.

9. A container assembly comprising:

a container and a seal ring configured to attach to the container in an attached configuration, wherein:
the container comprises:

21

a u-shaped crevice that is (i) internally located within the container, (ii) upwardly open toward a top opening of the container, and (iii) configured to engage with at least a portion of a lower seal structure of the seal ring; and

a crevice arm positioned radially inward from the u-shaped crevice, the crevice arm projecting from a sidewall of the container;

the seal ring comprises:

an outer sidewall comprising:

an arcuate portion for interfacing with a corresponding semi-circular bead of a sidewall of a container in the attached configuration;

an outer lip defining an annular channel having an upper closed end and a lower open end, the upper closed end being closer to the top of the container than the lower open end when the seal ring is in the attached configuration; and

a seal ring protrusion for engaging with the semi-circular bead in the attached configuration, the seal ring protrusion opposite an undercut surface of the annular channel;

an inner sidewall comprising a ring bead for engaging with a corresponding component on a container lid;

a floor extending from a first intersection between the floor and the inner sidewall to a second intersection between the floor and the outer sidewall; the lower seal structure, wherein the lower seal structure is configured to engage with the corresponding u-shaped crevice on the container and comprises:

a lower portion of the outer sidewall;

a cavity defined by a bottom structure of the lower portion of the outer sidewall, wherein the cavity comprises:

a first surface interfacing with a surface of the lower portion of the outer sidewall;

a second surface forming a rounded transition to an underside of the bottom structure; and

an upper interior surface extending between the first surface and the second surface,

wherein the cavity has a radially innermost edge that is bounded by a bottom surface that extends along at least a portion of the floor; and

a latch portion defined by the lower portion of the outer sidewall and the cavity; and

when the seal ring is in the attached configuration:

the cavity of the seal ring at least partially receives the crevice arm of the container and the u-shaped crevice of the container at least partially receives the latch portion of the seal ring to thereby form an interlocking seal between the container and the lower seal structure of the seal ring; and

a radial axis parallel to a bottom of the container simultaneously intersects the cavity of the seal ring, the crevice arm of the container, the u-shaped crevice of the container, the latch portion of the seal ring, and the bottom surface of the seal ring.

10. The container assembly of claim 9, wherein a width of the cavity is between 0.75 cm and 1.5 cm.

11. The container assembly of claim 10, wherein the bottom surface slopes radially outwardly and downwardly toward the bottom of the container when the seal ring is in the attached configuration, at an angle between 100 degrees and 130 degrees from the inner sidewall.

22

12. The container assembly of claim 11, wherein the ring bead protrudes substantially perpendicularly to the inner sidewall.

13. The container assembly of claim 12, wherein the ring bead is trapezoidal in shape and further comprises:

a front surface, wherein the front surface is parallel to an interior surface of the inner sidewall;

a top surface, wherein the top surface slopes downwardly toward the bottom of the container when the seal ring is in the attached configuration, from the interior surface of the inner sidewall to the front surface; and

a bottom surface, wherein the bottom surface slopes downwardly toward the bottom of the container when the seal ring is in the attached configuration, from the front surface to the interior surface of the inner sidewall.

14. The container assembly of claim 13, wherein a distance between the seal ring protrusion and the undercut surface is between 0.25 cm and 1.5 cm.

15. The container assembly of claim 14, wherein the annular channel, the seal ring protrusion, the arcuate portion, and the lower seal structure seal the seal ring with the container in the attached configuration.

16. The container assembly of claim 15, wherein the seal ring is plastic.

17. A container comprising:

a container body comprising a bottom, an uppermost end opposite the bottom and having a top opening, and an external wall extending from the bottom to the uppermost end and defining an interior cavity, the external wall comprising:

an exterior wall surface;

a container rim area proximate the uppermost end and comprising:

a latch surface extending outwardly from the exterior wall surface; and

a semi-circular bead formed by an interior wall surface; and

a ledge area below the container rim area, the ledge area integrally formed with the external wall and defining a u-shaped crevice that is open in a generally upward direction toward the uppermost end of the container body and a container body arm for engaging with a corresponding lower seal structure of a seal ring, the container body arm extending at least partially in the generally upward direction toward the uppermost end of the container body; and the seal ring comprising:

an outer sidewall comprising:

an arcuate portion for interfacing with the semi-circular bead of the interior wall surface of the container body when the seal ring is in an attached configuration with respect to the container body; and

a seal ring protrusion for engaging with the semi-circular bead in the attached configuration;

an inner sidewall forming a seal structure for sealing the interior cavity of the container with a lid; and the lower seal structure for engaging with the u-shaped crevice on the container body and comprising:

a cavity having a radially innermost edge that is bounded by a bottom surface extending from the radially innermost edge to the inner sidewall; and a latch portion defined by the outer sidewall and the cavity,

wherein when the seal ring and the container body are in the attached configuration:

23

the u-shaped crevice, the container body arm, the cavity, and the latch portion combine to form an interlocking seal between the container body and the lower seal structure of the seal ring; and each of (i) at least a portion of a radially outward wall surface of the u-shaped crevice, (ii) at least a portion of a radially inward wall surface of the u-shaped crevice, (iii) at least a portion of the container body arm, (iv) at least a portion of a radially outward wall surface of the cavity, (v) at least a portion of a radially inward wall surface of the cavity, (vi) at least a portion of the latch portion, and (viii) the bottom surface of the seal ring is intersected by a common radial axis that is perpendicular to a central vertical axis that passes through a center of the bottom of the container body, a center of the uppermost end of the container body, and a center of the seal ring.

18. The container of claim **17**, wherein:
the arcuate portion of the outer sidewall comprises a first thickness; and

5

10

15

24

a lower portion of the outer sidewall comprises a second thickness greater than the first thickness of the arcuate portion of the outer sidewall, the lower portion of the sidewall being closer to the bottom of the container body than the arcuate portion when the seal ring is in the attached configuration.

19. The container of claim **18**, wherein:

the seal ring comprises an outer lip defining an annular channel having an upper closed end and a lower open end, the upper closed end being closer to the uppermost end of the container body than the lower open end when the seal ring is in the attached configuration; and the seal ring protrusion is configured to engage with the semi-circular bead in the attached configuration, the seal ring protrusion being opposite an undercut surface of the annular channel.

20. The container of claim **19**, wherein the inner sidewall of the seal ring comprises a ring bead for engaging with a corresponding component on the lid to seal the interior cavity of the container.
